MOUNTING DEVICE

Russell L. Hohl, New York, N. Y.

Application January 7, 1936, Serial No. 57,942

9 Claims. (Cl. 189—88)

This invention relates to complementary parts cooperative for mounting one upon the other, and the invention is particularly adapted for employment in building structures and the like as for mounting sheathing panel units upon the substructure of a wall or ceiling.

This application is a continuation in part, of my co-pending application, Serial No. 711,176, filed February 14, 1934.

10 An object of the invention is to provide a novel cooperative relation between the complementary parts whereby one may be mounted upon the other without the aid of tools and with infinite adjustability as for exact accommodation to varying thickness of the secured panel units. To this end the invention embraces material of particular characteristics employed in members arranged to provide inter-engaging faces particularly disposed, all as will appear.

20 Further objects of the invention are to provide economical production of the parts, convenient application of them to the job, and pleasing appearance in the finished product.

Still further objects are to provide improved sealing means for the panel units.

Further objects and advantages will be apparent from the following description taken in connection with the accompanying drawing, in which Figs. 1 and 2 are perspective views showing complementary backing and finishing parts respectively, embodying and typifying the invention; Fig. 3 is a typical transverse section illustrating a complete assembly employing parts such as illustrated in Figs. 1 and 2; Fig. 4 is a view similar to Fig. 3 but illustrating a modification of the invention as to mounting of the parts, and their sealing means.

With reference now to the complementary backing and finishing parts, as illustrated in Figs. 1 and 2 of the drawing each is of uniform transverse section throughout its length as indicated.

The backing part has at its central portion channel-forming members providing parallel inwardly-opposed side faces 1, and inter-connected by a web portion 2 which together with feet 3 forms the base portion of the part. The backing part also includes a pair of laterally extending clamp members 4 spaced somewhat from its base portion, as indicated.

50 The finishing part, shown in Fig. 2, includes a central tongue member having parallel outwardly opposed faces 10 which may be split by the deep groove indicated so that the faces 10 are in a sense those of separate tongue members. Preferably, the two halves of the tongue member

are thicker at their base parts than at their free extremities, as illustrated. The finishing part also includes a pair of clamp members 40 laterally extending from and joining the base portions of the tongue member.

5 The spacing between the parallel faces 10 of the finishing part is substantially that of the faces 1 of the backing part so that the tongue member of the finishing part may be forced between the side faces 1 of the channel members 10 of the backing part and will there be frictionally retained as indicated Fig. 3. The thus cooperative faces of one of the parts, as of the finishing part, are smooth, while the corresponding faces of the other part, as the faces 1 of the backing part, have deformations, preferably longitudinally extending, so that in the assembly of the parts, bearing between cooperative pairs of faces is distributed over substantial areas in parallel planes but is not continuous.

20 According to this invention the material of the interengaging members of at least one of the parts and preferably both of them, and the relative disposition of the faces—that is their spacing—are such that when the finishing member is forced into its described assembly with the backing member there will be galling action between the cooperative pairs of faces. To this end the material of the cooperative member of at least one of the parts and preferably of both, is sufficiently ductile to permit such galling effect substantially without distortion of portions of the part other than at its frictionally engaged cooperative faces. Also, the material, proportions and arrangement of the parts is such that there may be some resilient lateral yielding of the interengaging members during the assembly.

25 I have found non-ferrous metals and particularly aluminum to be admirably suited for the purpose, especially where both parts are of aluminum. This metal has the proper ductility and resilience and also has such frictional properties that the parts are very firmly secured together by their mere assembly in the described manner. The cylindrical characteristics of the deformation indicated upon the faces 1 permit a certain flowing of the metal from the outer parts of the projections toward the spaces therebetween, producing firm contact with great holding power. Since the contact is in parallel planes the 30 assembly will be secure in any of innumerable relative positions of the parts, so that any desired spacing within reason between the clamp members 4, 40 may be satisfactorily accommodated.

The clamp members are adapted to receive the adjacent extremities of an adjacent pair of panel units 5, disposed generally in longitudinal planes to which the planes of the faces 1 and 10 are 5 perpendicular, as illustrated Fig. 3.

Preferably, recesses are provided in the inner faces of the clamp members to receive and retain plastic sealing means 6, inwardly extending projections 4' and 40' at the extremities of the 10 clamp members being effective to provide the described cavities. Additional projections 4" may be provided on the backing part clamp members to support the extremities of the panel units 5 against the plastic sealing means 6 as the assembly is had, so that in the assembly the sealing means may be applied to the finishing part before the latter is applied to the backing part.

In practice the backing part is mounted upon the substructure of a wall or the like, conventionally indicated at 7, as by screws 8 located in holes drilled through the base portion of the backing part on the job. The panel units 5 are next applied to the backing part, and the finishing part with its sealing means then applied to 20 both backing part and panel units, the finishing part being pushed home until the panel units are clamped between the complementary parts.

The parts being of relatively soft material, they may easily cut to proper lengths on the 30 job, as with a hacksaw. For economy, in some installations separate short lengths or sections of the backing part may be employed to mount a continuous single length of the finishing part by which the interruptions of the backing part 35 are concealed.

With reference now to the modification of Fig. 4, the backing part is mounted upon a runner 10 instead of a flat structure such as indicated in Fig. 3. Such runner 10 and its purpose is 40 fully set forth in my said copending application. It is sufficient here to state that the runner is generally of channel form with re-entrant sides between which the base portion of the 45 backing part extends, is positioned, and receives support, the backing part being assembled to the runner by endwise sliding.

In the backing part here shown the clamp members are provided with longitudinally extending cavities having re-entrant sides terminating in rather sharp edges, the cavities receiving and the edges retaining yieldable sealing means 60 such as hemp, felt or rubber beading. The beading extends beyond its cavities to have yieldable waterproof bearing upon the panel 55 units which are mounted by application of the finishing part as before but without plastic sealing means.

It will be observed that the panel units 50, Fig. 4, are much thinner than the panel units 5, Fig. 3, yet the finishing part is unchanged, as is the 60 backing part with the exception of its sealing means. The channel member portions of the parts are identical as before, and obviously, either backing part is capable of mounting in 65 either illustrated manner.

While the embodiments specifically illustrated and described have their clamp members extending at right angles to the interengaging faces of their tongue and channel members, for mounting of panel units disposed in a common general plane, it will be apparent that the clamp members could laterally extend at 45 degree angles to said faces, either rearwardly or forwardly, for mounting of panel units disposed in 70 planes at right angles to each other, as at 75

internal or internal corners between wall panels. Similarly, accommodation for any angular relationship between adjacent panel units could be provided, the interengaging faces of the tongue and channel members being preferably disposed in planes generally angularly bisecting those of the adjacent panel units to be mounted. Or, the clamp members on one side of the parts could be omitted entirely, as for finish at a door way or the like. Likewise it will be apparent that the 10 conformation of the base portion of the backing part may be otherwise than as specifically illustrated, to adapt the base part for mounting otherwise than in the typical manner shown.

Also, while as here shown the tongue member is upon the finishing part and the cooperative channel cavity in the backing part, this relationship could be reversed without altering the cooperative mounting effectiveness between the parts.

Production of the described complementary parts, both being preferably of relatively soft non-ferrous metal, is nicely had by extrusion. Aluminum, the metal which I found best suited for the purpose, lends itself admirably to production by extrusion. Such a production method permits any desired sectional contour with the uniformity and accuracy of dimension necessary for the spacing between the subsequently contacting faces, and also produces a finish of pleasing luster for the parts.

What I claim is:

1. In an article of the character described, complementary backing and finishing parts cooperative for mounting one upon the other, and having for the purpose longitudinally extending tongue and channel members with side faces proportioned and arranged to have frictional interengagement in parallel planes, at least one of said members being of sufficiently soft material 40 such as aluminum and at least one of each interengaging pair of said faces having such deformations that said interengagement will be accompanied by galling of at least one of the faces 45 of each pair in assembly of the parts.

2. In an article of the character described, complementary backing and finishing parts cooperative for mounting one upon the other, and having for the purpose longitudinally extending tongue and channel members with side faces proportioned and arranged to have frictional interengagement, at least one of said members being of relatively soft material such as aluminum so 50 that said interengagement will be accompanied by galling of at least one of said faces in assembly of the parts, said tongue member being split to provide slight resilience for said interengagement, and said split dividing said tongue member into halves and being so proportioned 55 that said halves diminish in thickness toward their free extremities.

3. In an article of the character described, complementary backing and finishing parts cooperative for mounting one upon the other, and having for the purpose longitudinally extending tongue and channel members with side faces proportioned and arranged to have frictional interengagement distributed over substantial areas in parallel planes, at least one of said members being of relatively soft material such as 65 aluminum whereby said interengagement will be accompanied by galling of its said faces in assembly of the parts.

4. In an article of the character described, complementary backing and finishing parts co- 75

- operative for mounting one upon the other, and having for the purpose longitudinally extending tongue and channel members with side faces proportioned and arranged to have frictional interengagement distributed over substantial areas in parallel planes, said members being of relatively soft material such as aluminum whereby said interengagement will be accompanied by galling of said faces in assembly of the parts.
5. In an article of the character described, complementary backing and finishing parts cooperative for mounting one upon the other, and having for the purpose longitudinally extending tongue and channel members with side faces proportioned and arranged to have frictional interengagement in parallel planes, one face of each interengageable pair being flat and the other having longitudinally extending deformations, said members being of material of such character that said interengagement will be accompanied by galling at said faces in assembly of the parts.
6. A structure having a pair of extrusions secured in assembled relation, one of which is extruded to form a longitudinally extending groove and the other to form a longitudinally extending tongue adapted to be pressed into said groove by relative lateral movement of said extrusions and to be held therein with the pairs of opposed sides of said tongue and groove in frictional contact, one side of at least one pair of said opposed sides being extruded to form a longitudinally extending bead of narrow width and the other side of said pair having a cooperating surface portion which when said tongue is pressed into said groove slides relatively over said bead laterally thereof and in contact therewith, one at least of said extrusions being of relatively soft material such as aluminum whereby pressing of said tongue into said groove will be accompanied by galling of at least one of the contacting surfaces constituted by said bead and said cooperating surface portion.
7. A structure having a pair of extrusions se-

cured in assembled relation, one of which is extruded to form a longitudinally extending groove and the other to form a longitudinally extending tongue adapted to be pressed into said groove by relative lateral movement of said extrusions with opposed surfaces of said groove and tongue in frictional contacting relation, the opposite walls of said groove being extruded to form a plurality of relatively narrow longitudinally extending beads cooperating with the adjacent surfaces of said tongue and adapted when said tongue is pressed into said groove to slide laterally over said surfaces in contact therewith, said extrusions being of relatively soft metal such as aluminum whereby pressing of said tongue into said groove will be accompanied by galling of the contacting surfaces of said tongue and beads.

8. In a structure of the character described, complementary extruded parts cooperative for mounting one upon the other, and having for the purpose longitudinally extending tongue and channel members with side faces proportioned and arranged to have frictional interengagement in parallel planes, at least one of said members being of sufficiently soft material such as aluminum and at least one of each interengaging pair of said faces as extruded having such deformations that said interengagement will be accompanied by galling of at least one of the faces of each pair in assembly of the parts.

9. In a structure of the character described, complementary extruded parts cooperative for mounting one upon the other, and having for the purpose longitudinally extending tongue and channel members with side faces proportioned and arranged to have frictional interengagement distributed over substantial areas in parallel planes, at least one of said members being of relatively soft material such as aluminum whereby said interengagement will be accompanied by galling of its said faces in assembly of the parts.
